UNITED STATES PATENT OFFICE.

FRANK W. GARRETT, OF JOHNSTOWN, PENNSYLVANIA, ASSIGNOR TO THE
LORAIN STEEL COMPANY, OF PENNSYLVANIA.
CIRCUIT-BREAKER.

SPECIFICATION forming part of Letters Patent No. 656,105, dated August 14, 1900.

Application filed December 1, 1899. Serial No. 738,751. (No model.)

To all whom it may concern:

Be it known that I, FRANK W. GARRETT, of Johnstown, in the county of Cambria and State of Pennsylvania, have invented a new and useful Improvement in Circuit-Breakers, of which the following is a full, clear, and exact description, reference being had to the accompanying drawings, which form a part of this specification.

My invention has relation to automatic circuit-breakers, and is designed to provide a device of this class in which advantage is taken, by means of simple character, of the fact that whenever lines of force forming part of two separately-generated magnetic fields traverse a common space there is a decided action between the two sets of lines, tending to so alter their paths that as many lines as possible shall coincide in direction.

The invention is also designed to prevent destructive arcing at the contacts and to provide a circuit-breaker which in general is of efficient and reliable character.

My invention consists, broadly, in a circuit-breaker whose movable contacts are carried by a member placed in a magnetic field and itself capable of generating a magnetic field whose lines of force do not coincide in direction with those of the field in which said member is primarily placed, together with means for restraining the movement of said member under normal conditions in the connected circuit and for permitting its movement under abnormal conditions in said circuit.

My invention also consists in a circuit-breaker having means whereby the circuit is simultaneously broken at a number of points or places connected in series and, under other conditions which prevent destructive arcing; also, to provide means whereby the circuit may be broken arbitrarily whenever desired and for reestablishing the same.

Finally my invention consists in the novel construction, arrangement, and combination of parts, all as hereinafter described, and pointed out in the appended claims.

In the accompanying drawings, in which I have shown an embodiment of my invention, Figure 1 is a plan view of a circuit-breaker, partly broken away. Fig. 2 is a transverse vertical section of Fig. 1. Fig. 3 is a diagram-

matic view showing the circuit connections. Fig. 4 is a detail view of the pawl device which normally restrains the movement of the armature. Fig. 5 is a detail view of one of the 55 collector-rings and brushes, and Fig. 6 is a detail view showing the main contacts and bridging-piece.

The letter A designates the core or yoke of an electromagnet having parallel extended 60 pole-pieces A'. B is a coil of coarse insulated wire which is wound upon said yoke or core and included in the main-line circuit-wire C. D is a movable member which I shall hereinafter term the "armature" and which consists of a number of similar iron plates secured to a shaft E, from which they are insulated and upon which they are spaced from each other by interposed insulating blocks or pieces E'. The shaft E is supported in bearings E² and passes centrally through the plates, which extend diametrically thereto, with their ends adjacent to the two pole-pieces A'. In the drawings I have shown five of these plates; but a greater or less number may be 75 employed, according to the pleasure of the maker or the extent to which it is desired to subdivide the arc in breaking circuit. Each plate has in each of its arms a cylindrical recess d, forming a seat for the wires of the 80 coil F, which is wound longitudinally of the armature in a similar manner to a coil of an ordinary drum-armature, the wire being wound in through the slots d', leading to the recesses. Fine insulated wire is used for this 85 coil, and its two ends are connected to collector-rings f f', insulated from each other upon the shaft E. Brushes g g' bear, respectively, upon these rings, said brushes being connected to the line-wire C upon opposite 90 sides of the coil B, so that said coil B and the coil F are connected in parallel with each other.

H designates a series of contact-pieces, preferably of copper, one of which is secured to 95 each end of each of the armature-plates over the slots d', as best seen in Fig. 2.

K designates spring contact-fingers arranged in two series, the fingers of one series engaging with the respective contact-pieces 100 H at one end of the armature-plates and those of the other series engaging with the respec-

tive contact-pieces at the opposite ends of said plates. The fingers of both sets are normally all connected in series by short connections *k* and the contacts *H* and armature-plates in the manner clearly shown in Fig. 3, the connections *k* uniting adjacent pairs of fingers of each set, and opposite fingers on the two sets being connected through the armature-plates and contacts. The first finger *K* of one set is electrically connected to a main contact *L*, to which one side of the circuit *C* is also connected, and the last contact-finger of the opposite set is similarly connected to a second main contact *L'*, to which the other side of the circuit *C* is connected.

M is a bridging-piece, composed of copper laminae, (see Fig. 6,) but which may be of any other suitable character, for connecting the contacts *L L'*.

N is a handle on the projecting end portion of the shaft *E*, by means of which the latter, with the armature, may be manually operated.

P is a catch or detent plate secured on the shaft *E* and formed with a notch *p* and a stop projection *p'*.

R is a pawl which normally engages the notch *p* to hold the armature in the position shown in Fig. 2.

S is a compression-spring bearing at one end on the pawl-arm and seated at its opposite end against a cap *S'*, upon which bears an adjusting-screw *S''*.

It will be readily seen from Fig. 2 that inasmuch as the plane of the coil *F* is normally parallel to the lines of force of the electromagnet *A B* the lines of force of its field will be projected at right angles to those of the said magnet and that consequently there is a force tending to move said coil and the armature to a position where the lines of force of the two fields will coincide in direction, or, in other words, to move the armature through an arc of ninety degrees. This movement is, however, under normal conditions forcibly restrained by the action of the pawl *R*. When the current passing in the circuit *C* becomes abnormally great, the strength of the magnetic fields becomes proportionately increased, thereby increasing the torque on the coil *F* to such an extent as to overcome the restraining action of the said pawl and turn the armature, the pawl riding out of the notch *p'*.

By reference to Fig. 3 it will be seen that under normal conditions, with the armature in the position shown in Fig. 2, the contacts *L L'* and bridging-piece *M* form a short circuit to the fingers *K* and contacts *H*, which are in a secondary or shunt circuit. As soon, however, as the armature commences to move, the bridging-piece *M* immediately leaves the contacts *L L'*, breaking the said short circuit and sending the current through the shunt or secondary circuit, the fingers *K* being still in engagement with the contacts *H*. This prevents any arcing at the main contacts, and when momentarily after the break occurs at

the contacts *H* the arc is subdivided to such an extent as to prevent its destructive action, particularly in view of the fact that the break occurs in the magnetic field of the coil *B*.

By adjusting the spring *S* the restraining action of the pawl *P* may be increased or decreased, and this enables the instrument to be so adjusted as to respond and break circuit upon any predetermined increase of current in the circuit *C*. By turning the handle *N* circuit may be arbitrarily broken at any time. Said handle also forms means for resetting the armature to operative position.

I do not wish to limit myself to the particular embodiment of my invention herein shown and described, as my invention is obviously much broader than such embodiment and various instruments may be constructed which involve all the essential features of the invention, although differing considerably from the construction and arrangement shown.

Having thus described my invention, what I claim, and desire to protect by Letters Patent, is—

1. In a circuit-breaker, the combination of means in the main circuit of the instrument for producing a magnetic field, the armature movably supported in said field and carrying a coil whose plane is normally substantially parallel to the lines of force of said field, means for normally restraining movement of said armature, and for permitting such movement under abnormal conditions, means for effecting a circuit through the body of said armature independent of its coil, and a normal short circuit around the last-named circuit.

2. A circuit-breaker having a movable armature journaled in a magnetic field, a coil on said armature and connections to said coil from the main circuit, means for normally holding said armature in a position in which the lines of force of the said coil do not have a maximum coincidence with the lines of force of the field in which the armature is journaled, means for effecting a circuit through the body of said armature independent of its coil, and means whereby said circuit is broken by a predetermined movement of said armature.

3. A circuit-breaker having a movable member or armature situated in a magnetic field, a coil on said member or armature, a series of contacts on the periphery of said member or armature within the said field, and means for effecting a circuit through the said contacts and for breaking the same at each of said contacts upon a predetermined movement of the said member or armature.

4. In a circuit-breaker, an electromagnet whose coil is energized from the main circuit, an armature movably supported between the poles of said magnet, and carrying the movable contacts of the instrument said contacts being situated in the arc-disrupting field of said magnet and a coil on said armature con-

nected in parallel with the coil of said magnet, together with means whereby said coil is normally held in such a position in the field of said magnet that the lines of force generated by the coil do not have a maximum coincidence in direction with the lines of force generated by the said magnet.

5. In a circuit-breaker having fixed and movable contacts, the combination with an electromagnet whose coil is connected in the main circuit, of an armature journaled between the poles of said magnet and carrying movable contacts which normally complete two circuits, one of which short-circuits the 10 other and means whereby those contacts forming part of the short circuit lose their connections in such circuit upon movement of said armature before the other of said circuits is broken, said armature having a coil connected in parallel with the field-magnet coil, and means for normally holding said coil in a plane parallel to the direction of the lines of force of the said magnet.

15. In a circuit-breaker, the combination with an electromagnet and an armature supported in the field of said magnet and itself capable of generating a magnetic field, of a plurality of contacts secured to said armature and a series of contact-fingers engaging said contacts and connected in series with each other and also connected to line, said contacts and contact-fingers forming a shunt-circuit through the body of said armature.

20. In a circuit-breaker, the combination with an electromagnet, of an armature journaled in the field of said magnet, and carrying the movable contacts of the instrument, a coil on said armature, means for energizing the said coil and a pawl device for normally holding the armature against movement and for releasing the same under abnormal conditions of the said coils.

25. In a circuit-breaker, the combination with an electromagnet, of an armature journaled in the field of said magnet, and carrying the movable contacts of the instrument, a coil on said armature, and means for energizing the said coil, and a pawl device for normally holding the armature against movement and for releasing the same under abnormal conditions of the said coils, together with means for adjusting the action of said pawl to vary its restraining action on the armature.

30. In a circuit-breaker, the combination of an electromagnet, an armature in the field of said magnet and carrying movable contact devices, said armature having a coil, means for energizing the said coil, and fixed contact devices co-operating with the said movable contact devices, together with means for restraining the movement of the said armature under normal conditions, means for normally short-circuiting the circuit through said movable contacts and fixed contact devices, and for breaking such short circuit upon the initial movement of said armature.

35. In a circuit-breaker, the combination of an electromagnet whose coil is connected with the circuit, an armature in the field of said magnet and carrying movable contacts, said armature having a coil and circuit connections for energizing with said coil, fingers for engagement with the said contacts, said fingers being electrically connected with the 40 circuit and with each other, a pair of main contacts, a bridging-piece for said contacts carried by the armature and forming with said main contacts a short circuit for the said movable contacts and fingers in the normal 45 position of the armature.

40. In a circuit-breaker, the combination with an electromagnet whose coil is connected with the circuit, of an armature journaled in the field of said magnet and having a coil also 50 connected in circuit, a plurality of insulated contacts on said armature, a plurality of contact-fingers for engagement therewith, said fingers being connected to opposite terminals of the line and in series with each other, and 55 means for normally connecting the line-terminals to short-circuit said fingers.

45. In a circuit-breaker of the character described, the combination with an electromagnet connected with the circuit, of an armature journaled in the field of said magnet, and composed of a plurality of insulated plates secured to a shaft, a coil seated in slots of the said plates, and also connected with the circuit, a plurality of contacts carried by 60 the said plates, and fixed contact-fingers engaging the said contacts and connected with the circuit.

50. In a circuit-breaker of the character described, the combination with an electromagnet, of the armature journaled in the field of said magnet, said armature comprising a series of insulated plates centrally secured on a shaft, and slotted at each end portion, and a coil seated in the slots of said plate, connections for energizing the said coil, and means for normally restraining the movement of the said armature, together with a series of contacts closing the slots in said plates, and co-operating fixed contacts and connections 70 for effecting a circuit through the said plates.

55. The herein-described circuit-breaker, comprising the electromagnet having its coil connected in the circuit, the armature composed of series of insulated slotted plates situated between the poles of said magnet, a journaled shaft to which said plates are secured, and a coil seated in the slots of said plates, connections for energizing the said coil, a contact on each end of each of said plates, 80 contact-fingers engaging the same, and electrically connected in series with each other and also in the line-circuit, means for normally short-circuiting the said fingers, and means for normally holding said armature 85 with its coil in a plane substantially parallel to the lines of force of said electromagnet, and for releasing said armature under abnormal conditions in the circuit.

15. In a circuit-breaker, an armature composed of a shaft, a series of separated metal plates secured thereon and insulated therefrom and from each other, and having contact-pieces at their ends, a coil seated in slots in said plates, and brushes bearing on said shaft and electrically connected to the line in which the circuit-breaker is placed.

16. In a circuit-breaker, an armature, means carried thereby for producing a magnetic field, external means for producing a surrounding non-coincident field, a series of con-

tacts carried by the said armature, and fixed contact devices coöperating therewith and engaging the same in the said magnetic field, whereby arcs formed by the separation of said contacts are subject to the disrupting action of said field.

In testimony whereof I have affixed my signature in presence of two witnesses.

FRANK W. GARRETT.
